US0D1030710S

(12) **United States Design Patent** (10) Patent No.: **US D1,030,710 S**
(45) Date of Patent: ** Jun. 11, 2024

(54) **IN-CAR SPEAKER**

(71) Applicant: **ALPS ALPINE CO., LTD.**, Tokyo (JP)

(72) Inventor: **Masatada Muramoto**, Tokyo (JP)

(73) Assignee: **ALPS ALPINE CO., LTD.**, Tokyo (JP)

(**) Term: **15 Years**

(21) Appl. No.: **29/844,252**

(22) Filed: **Jun. 28, 2022**

(30) **Foreign Application Priority Data**

Feb. 2, 2022 (JP) ..... 2022-002006 D

(51) **LOC (14) Cl.** **14-01**

(52) **U.S. Cl.**
